UNITED STATES PATENT OFFICE.

GEORGE E. HUMBERT, OF NEW YORK, N. Y.

SIGHT-SETTING DEVICE.

SPECIFICATION forming part of Letters Patent No. 789,545, dated May 9, 1905.

Application filed April 11, 1904. Serial No. 202,548.

To all whom it may concern:

Be it known that I, GEORGE E. HUMBERT, a citizen of the United States, and a resident of the city of New York, borough of Brooklyn, in the county of Kings and State of New York, have invented a new and Improved Sight-Setting Device, of which the following is a full, clear, and exact description.

The invention relates to sights for rifles and other firearms; and its object is to provide a new and improved sight-setting device arranged to enable the marksman to conveniently and accurately set the sight to exact range for fine shooting.

15 The invention consists of novel features and parts and combinations of the same, as will be more fully described hereinafter and then pointed out in the claims.

A practical embodiment of the invention is 20 represented in the accompanying drawings, forming a part of this specification, in which similar characters of reference indicate corresponding parts in all the views.

Figure 1 is a perspective view of the improvement as applied to a rifle-sight. Fig. 2 is a face view of the improvement. Fig. 3 is a sectional side elevation of the same as applied, and Fig. 4 is a sectional plan view of the improvement on the line 4 4 of Fig. 3.

30 The rifle-sight illustrated in Fig. 1 consists of the usual base A, secured to the top of the barrel B of the rifle, and on the said base A is pivoted a sight-standard C, on which is held vertically adjustable the sight proper, D, 35 adapted to be fastened in place on the standard C by a suitable set-screw E. The sight-setting device is mounted on a frame F, adapted to fit onto the front face of the sight-standard C, and on the upper end of the said frame 40 F is secured a flange or abutment member G, adapted to rest on the top of the sight-standard C, as plainly indicated in Figs. 1 and 3.

On the frame F is mounted to slide up and down a stop H, adapted to be engaged by the 45 bottom of the sight D, as indicated in Figs. 3 and 4, and the said stop H is provided with a threaded block H', mounted to slide up and down in suitable guideways formed on the frame F. In the block H' screws a screw- 50 rod I, journaled at its upper and lower ends

in suitable bearings in the frame F, and on the upper end of the said screw-rod I is secured a pinion J, in mesh with a large bevel gear-wheel K, mounted to turn on a stud K', supported by a cross-bar F', forming part of 55 the frame F. (See Figs. 3 and 4.) On the back of the bevel gear-wheel K is arranged a graduation L, indicating on a graduated index N in the shape of a bar extending diametrically over the graduation, the ends of 60 the bar being attached to arms F² and F³, projecting from or forming part of the frame F. Now by the operator turning the gear-wheel K a rotary motion is given to the bevel-pinion J to turn the screw-rod I, and thereby 65 cause the block H' and its stop H to slide up or down according to the direction in which the bevel gear-wheel K is turned.

In order to hold the bevel gear-wheel K against accidental turning, a retaining-lever 70 O is provided in engagement with the peripheral face of the bevel gear-wheel K and fulcrumed on the frame F, as plainly shown in Fig. 2. A spring O' presses the lever O, and the latter is provided with a finger-piece 75 O², adapted to be engaged by the finger of the operator for swinging the lever O out of engagement with the gear-wheel K when it is desired to turn the gear-wheel for setting the stop H, as previously explained.

80 On one side of the frame F is arranged a graduation P, corresponding to a graduation Q on the sight-standard C, both graduations indicating the desired range in hundreds of yards. Now the graduation L on the back of 85 the bevel gear-wheel K indicates corresponding hundreds of yards and subdivisions thereof—that is, the graduation L is formed by concentric bands, each of which has a graduation of one hundred yards and subdivisions, 90 preferably of two and one-half yards each. By reference to Fig. 2 it will be seen that the end of the graduation on one concentric band registers with the beginning of the graduation on the next following band, the end of the 95 graduation and the beginning of the following graduation being preferably indicated by large adjacent circles, while the subdivisions of a graduation on a band is indicated by dots, circles, or the like. As shown in Fig. 2, 100

twenty-five, fifty, and seventy-five yards are indicated by large circles, and two and one-half yards by dots; but I do not limit myself to this peculiar marking, as lines or the like 5 may be employed for the same purpose.

The markings on the graduation L are so arranged relative to the stop H that when the end of the graduation for seven hundred yards and the beginning of the graduation for 10 eight hundred yards registers with the edge of the index N then the stop H stands at "8" on the graduation P, and when the gear-wheel K is now turned until the first twenty-five yards' mark registers with the index N then 15 the stop H has been moved upward on the frame F one-quarter the distance between the marks "8" and "9" on the graduation P, thus indicating that the setting device has been set for eight hundred and twenty-five 20 yards. In case it is desired to set the setting device to indicate, say, seven hundred and eighty-five yards, as illustrated in Figs. 1, 2, and 3, then the operator turns the bevel gear-wheel K until the marking "85" on the band 25 for seven hundred yards registers with the bar N.

As shown in Fig. 2, the bar N is preferably provided with an index N', corresponding to the concentric bands of the graduation L to 30 facilitate the setting of the gear-wheel, as before mentioned.

When it is desired to set the gun-sight D, say, to eight hundred and twenty-five yards range, then the gun-sight D is moved up a 35 distance above the numeral "8" on the graduation Q of the sight-standard C and is then fastened in place by the set-screw E. The operator now places the setting device in position on the standard C by engaging the abutment member G with the top of the sight-standard C, as illustrated in Figs. 1 and 3, and 40 then the operator loosens the set-screw E and slides the sight D downward until the bottom thereof rests on the top of the stop H, set, as 45 previously explained, to eight hundred and twenty-five yards. The set-screw E is then screwed up to fasten the sight in place, and then the sight-setting device is removed from the sight-standard C.

50 From the foregoing it will be seen that the sight-setting device is first set by the operator to the desired range, whatever that may be, and then applied to the sight-standard C,

and finally the sight D is moved until the latter abuts on the stop H, after which the sight is 55 fastened in place by the set-screw E, and the sight is now set to the desired range.

It is understood that the stop H is controlled by a micrometer formed by the graduated gear-wheel K, the bar N, and the screw-rod I, having the bevel-pinion J and screwing in the block H' of the said stop H.

Having thus described my invention, I claim as new and desire to secure by Letters Patent—

1. A sight-setting device for removable attachment to a sight for a firearm, comprising a micrometer, and a movable stop for engagement by the sight and controlled by the micrometer, the latter being constructed of a vertically-mounted screw-rod having a pinion 70 at its upper end, a large bevel gear-wheel engaged by said pinion and having concentrically-disposed graduations on the back thereof, and a rigid graduated index-bar extending diametrically across such graduations. 75

2. A sight-setting device for removable attachment to a sight for a firearm, comprising a micrometer, a movable stop for engagement by the sight and controlled by the micrometer, and a fixed member for engagement with the sight-standard, said micrometer being constructed of a screw carrying a pinion, a large bevel-gear engaged by said pinion, and having concentrically-disposed graduations thereon, and a rigidly-supported index device extending across such graduations. 80

3. A sight-setting device for removable attachment to a sight, comprising a frame having a fixed member for engagement with the sight-standard, a stop slidable on the frame 90 opposite the fixed member and adapted to be engaged by the sight, a screw-rod mounted to turn in the frame and screwing in the said stop, to move the latter up and down, a pinion on the screw-rod, a gear-wheel journaled 95 on the frame and in mesh with the pinion, a graduation on the back of the gear-wheel, and an index-bar fixed on the frame, for setting the graduated gear-wheel.

In testimony whereof I have signed my name 100 to this specification in the presence of two subscribing witnesses.

GEORGE E. HUMBERT.
